PAIR OF SPECTACLES

Beryl B. Knowles, North Attleboro, Mass., assignor to
Fairfield Optical Company, Mansfield, Mass., a cor-
poration of Massachusetts

Application July 31, 1958, Serial No. 52,000

Term of patent 7 years

(Cl. D57—1)

Fig. 1.

Fig. 2.

Fig. 1 is a perspective view of a pair of spectacles embodying my new design; and

Fig. 2 is an enlarged fragmentary elevational view of the rear portion of the left temple.

The right temple, not fully shown in elevation, is like the left temple which is shown.

The dominant features of my design reside in the portions shown in full lines in the drawing.

The pattern of surface ornamentation as viewed in detail in Fig. 2 constitutes the pattern of ornamentation followed throughout the spectacles.

I claim:

The ornamental design for a pair of spectacles, substantially as shown and described.
